(57) **CLAIM**

I claim the ornamental design for a seat, as shown.

DESCRIPTION

FIG. 1 is a perspective view of a first embodiment of a seat showing my new design in the form of a chair;

FIG. 2 is a perspective view of a second embodiment of a seat in the form of a love seat;

FIG. 3 is a perspective view of a third embodiment of a seat in the form of a sofa;

FIG. 4 is a top plan view thereof;

FIG. 5 is a front elevational view thereof;

FIG. 6 is a left side elevational view thereof; and,

FIG. 7 is a right side elevational view thereof.
